UNITED STATES PATENT OFFICE

164,681

INFANT'S CRIB

Abraham G. Feldman, Chicago, Ill., assignor to Storkline Furniture Corporation, Chicago, Ill.,
a corporation of Illinois

Application September 2, 1950, Serial No. 12,034

Term of patent 7 years

(Cl. D5—5)

To all whom it may concern:

Be it known that I, Abraham G. Feldman, a citizen of the United States, residing in Chicago, in the county of Cook and State of Illinois, have invented a new, original, and ornamental Design for an Infant's Crib, of which the following is a specification, reference being had to the accompanying drawing forming part thereof, in which the single figure of the drawing is a perspective view taken from one end and somewhat to one side of an infant's crib embodying my new design, a mattress being shown in dotted outline.

The main panel of the headboard is similar in appearance to the panel portion of the footboard.

I claim:

The ornamental design for an infant's crib, substantially as shown and described.

ABRAHAM G. FELDMAN.
